UNITED STATES PATENT OFFICE

FRANK TAMBORELLO, OF MILWAUKEE, WISCONSIN

AVIATOR'S CAP

Application filed June 19, 1929. Serial No. 372,180.

This invention relates to a new and improved sanitary aviator's cap.

One of the objects of my invention is the provision of a removable lining for aviators' caps whereby a soiled lining can be quickly and readily removed and replaced by a new one.

Another object of the invention is the provision of a detachable lining for caps particularly aviators' caps, whereby the lining and the cap are provided with co-engaging fastening elements so that the lining can be quickly placed in position and secured against movement within the body of the cap.

15 A further object of the invention is the provision of a lining for aviators' caps preferably of felt or similar material which is detachably secured within the cap and provided with the usual ear flaps and downwardly depending head flange so that the lining will readily conform to the interior shape of the cap and can be quickly and readily placed in position or removed from the cap.

20 A still further object of the invention is the provision of an aviator's cap having a removable lining providing a cap of sanitary type and wherein the construction of the cap is such as to provide an inturned edge at the front of the cap to form a sweat band 25 extending entirely across the forehead portion of the cap, so as to eliminate the continuous wear of the lining at this point and also prevent the lining from becoming saturated with perspiration which would render it stiff and comparatively unpleiable.

25 With the above and other objects in view, the construction of my invention consists in the novel features of construction, the combination and arrangement of parts herein- 30 after more fully set forth, pointed out in the claim and shown in the accompanying drawings wherein:

35 Figure 1 is a perspective view of an aviator's cap constructed in accordance with my invention, illustrating the application of the same;

Figure 2 is a detailed sectional view on the line 2—2 of Figure 1;

40 Figure 3 is a sectional view on the line 3—3 of Figure 1;

45 Figure 4 is a sectional view on the line 4—4 of Figure 1; and

50 Figure 5 is a sectional view on the line 5—5 of Figure 1.

In carrying out my invention, the outer 55 casing or body portion of the cap may be of the usual leather type and includes the dome-like head piece 1, made up of a plurality of sections sewed together, and at the lower edge of the head piece 1 is a depending flange 2 which preferably extends from the forehead or the temple part all the way around the back of the head and projecting downwardly from the flange 2, in order to cover the ears and extend beneath the lower 60 jaws of the party wearing the cap are the tabs 3, and attached to these tabs 3 is any suitable type of detachable securing means for connecting the tabs beneath the chin of the wearer.

65 The above is substantially the usual construction of the ordinary leather aviator's cap and in order to provide a sanitary lining for this type of cap, I provide a single piece 70 of felt or other desirable material cut to conform to the shape of the dome-like head piece 1, the depending flange 2 and the tabs 3. This lining which is generally indicated at 4 can be stamped in a single piece to conform to 75 the shape of the cap as stated, and in order to detachably connect the lining to the interior of the cap, the exterior surface of the lining is provided with a plurality of snap fasteners 5 adapted to cooperate with similar fasteners 6, carried by the interior of the 80 body of the cap, the flange 2 and the tabs 3. These fasteners may be of any well known type, preferably of the head and socket type 85 so that the lining may be quickly placed in position and secured against movement relative to the body of the cap.

90 It will be noted that the edges of the tabs and the flange 2 are provided with a binder 7, and the entire outer edges of the removable lining 4 is also provided with a binding 8. 95 However, the part of the head piece 1 which extends down onto the forehead of the wearer is somewhat longer than the other sections of the head part and the lower edge is turned upwardly onto the inner face of the lining, 100

as shown in Figure 2, forming a suitable sweat band 9 extending from each end of the flange 2 across the forehead. This sweat band protects the lining against wear at this point and also prevents the lining from absorbing the perspiration usually occurring on the forehead, and is not secured down in any particular manner but can be folded outwardly when the lining is placed in position and then folded back to the position shown in Figure 2 after the lining has been placed within the body of the cap.

It will be apparent from the foregoing that I have provided a useful, sanitary lining for caps, particularly the caps or helmets which are worn by aviators, which can be quickly and readily placed in position upon the interior of the cap or removed when so desired.

In view of the fact that the lining can be cut in a single piece, the device is very inexpensive and at the same time serves a very useful purpose, in that it not only provides a sanitary lining but different weights of material can be used for adding to the comfort of the party wearing the cap, as the lining can be made of comparatively heavy felt to withstand extreme low temperature.

While I have shown and described the preferred embodiment of my invention, it will be apparent that slight changes may be made in the construction when putting the invention into practice without departing from the spirit of the same or the scope of the appended claim.

35 I claim:

A device of the class described including a head-shaped body member having a depending flange at the sides and back thereof, tabs depending from the lower edge of the flange at the ends thereof, means for detachably connecting the outer ends of the tabs, a removable lining formed of a single piece of material adapted to cover the entire interior surface of the body, the flange and the tabs, fastening members carried by the lining, fastening members carried by the body, flange and tabs for detachably engaging the fastening members on the lining to retain the lining in position, and an integral depending flexible part at the front of the body adapted to be folded inwardly over the edge of the lining to form a sweat band.

In testimony that I claim the foregoing I have hereunto set my hand at Milwaukee, in the county of Milwaukee and State of Wisconsin.

FRANK TAMBORELLO.
